(57) **CLAIM**

The ornamental design for a hose splitter as shown and described.

DESCRIPTION

1.1 : Back

1.2 : Front

1.3 : Bottom

1.4 : Front bottom view

1.5 : Left

1.6 : Top

The broken lines and areas within depict portions of the hose splitter that form no part of the claimed design.

The use of the symbol on the design article forming part of the claimed design is a registered trademark of RGA GIGI LLC.
